UNITED STATES PATENT OFFICE.

EMORY G. PENNINGTON, OF MIAMI, TEXAS.

CALENDAR.

1,346,764.

Specification of Letters Patent. Patented July 13, 1920.

Application filed January 6, 1920. Serial No. 349,703.

To all whom it may concern:

Be it known that I, EMORY G. PENNINGTON, a citizen of the United States, residing at Miami, in the county of Roberts and State 5 of Texas, have invented new and useful Improvements in Calendars, of which the following is a specification.

This invention comprehends the provision of a calendar wherein the body or backing 10 thereof is provided with a slot through which each of the respective pages of the calendar is passed, subsequent to its use, so that the said pages can be preserved for future reference, means being provided to 15 normally cover the slot, and to conceal the latter and the used pages from view, thus affording the calendar a neat appearance.

The nature and advantages of the invention will be better understood when the following detail description is read in connection with the accompanying drawings, the invention residing in the construction, combination and arrangement of parts as claimed.

In the drawings forming part of this specification like numerals of reference indicate similar parts in the several views and wherein:

Fig. 1 is a front elevation of a calendar constructed in accordance with my invention.

Fig. 2 is a view of the reinforcing element for the flexible hinge.

Fig. 3 is a similar view of the adhesive strip.

Fig. 4 is a similar view of the cover.

Fig. 5 is a view of the facing for the said strip.

Fig. 6 is a view similar to Fig. 1 showing 40 the cover elevated and the slot interposed.

Fig. 7 is a view showing one of the pages passed through the slot.

Fig. 8 is a vertical sectional view through 45 the calendar showing one of the pages passed through the slot and its cover in normal position.

Referring to the drawings in detail, 10 indicates the body or backing of the calendar which may be constructed from any suitable material and of any desired dimensions, and provided with an eyelet 11 at one end for suspending the calendar from a suitable support. The body 10 is provided with a transverse elongated slot 12 at an appro-

priate point in its length, the purpose of 55 which will be hereinafter described. The edges of the slot are reinforced by any suitable material such as indicated at 13. The pages 14 of the calendar are secured at a point immediately beneath the lower edge of the 60 slot in the usual well known manner. Approximately one-half of each page is utilized for the data with reference to the days of the month, the other half of each page, as well as the major portion of the body or 65 backing 10, being utilized for advertising matter.

Secured to the body 10 at a point immediately above the slot 12, is a narrow strip of cardboard or other suitable material 15. 70 This strip serves as a reinforcement for the flexible hinge for the cover 15' which normally covers the slot 13. The hinge is in the nature of a strip of adhesive material 16 which has one edge secured along the reinforcing element 15 and its opposite edges secured to one side of the cover 15'. A strip 17 covers the adhesive strip 16, being secured thereto in any suitable manner, the strip 17 being folded over the upper edge of the reinforcing element and secured to the back thereof. The strip 16 is to give the hinge and cover 15', at its point of connection with the hinge, a nice finish. The cover 15' 80 on one side contains advertising matter, 85 while the opposite or under side of the cover is used to contain data relative to the more important days of the year, and on which particular page of the calendar they will be found. 90

In use of the calendar the parts are normally arranged in the manner illustrated in Fig. 1, in which position of parts the cover 15' normally conceals from view the slot 12. Subsequent to the use of each page 14 of the 95 calendar, the cover 15' is elevated to the position illustrated in Fig. 6, and said page passed through the slot 12 to lie at the rear of the calendar. The cover 15' is then returned to its normal position to conceal both 100 the slot and the used page, thus affording the calendar a neat appearance. In this manner the respective pages of the calendar, subsequent to their use may be preserved for future reference. The pages of the calendar 105 may project beneath the lower edge of the body 10, in which instance the pages on the front of the calendar conceal from view

the lower edges of the used pages after the latter have been passed through the slot 12, or the body 10 of the calendar may be of such size as to terminate beneath the lower 5 edge of the pages 14 for this purpose.

While it is believed that from the foregoing description the nature and advantages of the invention will be readily apparent I desire to have it understood that I do not 10 limit myself in this connection and that such changes may be resorted to when desired as fall within the scope of what is claimed.

What is claimed is:

- 15 1. A calendar comprising a backing having a transverse slot, a reinforcing element embracing the edges of said slot, a plurality of pages secured to the back and immediately beneath the slot and adapted to be singly passed through the slot, and means normally covering said slot, concealing the slot from view.
- 20 2. A calendar comprising a backing having a transverse slot, a plurality of pages secured to the back and immediately beneath the slot and adapted to be passed singly through the slot, and a cover hinged to said

backing and arranged to normally cover the slot to conceal the letter from view.

3. A calendar comprising a backing having a transverse slot, a plurality of pages secured to the back and immediately beneath the slot and adapted to be singly passed through the slot, a transversely disposed reinforcing element secured to the backing and immediately above the slot, and a cover hingedly associated with said transverse element and normally disposed to cover the slot from view.

4. A calendar comprising a backing having a transverse slot, a plurality of pages secured to the backing and immediately beneath the slot and adapted to be passed through the slot, a transversely disposed reinforcing element secured to the backing and immediately above the slot, a strip of flexible material secured to said reinforcing element, a cover for the slot, said cover being carried by the flexible material and normally disposed to cover the slot from view, the flexible material providing a hinge for the cover.

In testimony whereof I affix my signature.
EMORY G. PENNINGTON.
